UNITED STATES PATENT OFFICE.

MARY ALICE GIVENS, OF VICTOR, COLORADO.

FINGER RING FOR HANDLING PAPER SHEETS.

Application filed March 5, 1921. Serial No. 449,613.

To all whom it may concern:

Be it known that I, MARY A. GIVENS, a citizen of the United States, residing at Victor, county of Teller, and State of Colorado, 5 have invented certain new and useful Improvements in Finger Rings for Handling Paper Sheets; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 The object of this invention is to provide a ring for use in turning or handling sheets of paper or pages of books, and for dealing cards and for similar uses.

Briefly, the invention comprises a ring 20 having clinging means thereon, preferably in the form of a rubber band which may be readily renewed, said clinging means being adapted to engage the sheet or card to remove the same. Preferably, the ring also has 25 an enlarged shield for engagement with the ball of the finger or thumb to readily retain the same thereon.

In the drawings:

Fig. 1 is an end elevation of the device, as 30 indicated by line 1—1 of Fig. 2;

Fig. 2 is a longitudinal section taken on line 2—2 of Fig. 1;

Fig. 3 is a longitudinal section at right angles to the view of Fig. 2 as indicated by 35 line 3—3 of Fig. 2;

Fig. 4 is a cross section taken on line 4—4 of Fig. 2; and

Fig. 5 is an elevation showing the device in use.

40 The invention comprises a ring or band 10 having an enlarged plate 12 on one side thereof and connected thereto by web portions 14, one end of said plate or shield 12 being elongated and tapered, as indicated at 45 15. The plate 12 and its extension 15 are

curved or cupped slightly as shown for the purpose of fitting the ball of the finger or thumb in order to assist retention of the device thereon, the finger being adapted to engage the inner face 112 of plate 12 as illustrated in Fig. 5. The end of the shield or plate 12 opposite from the extension 15 is provided with a transverse inwardly extending slot 16 producing an outer integral tongue 18 spaced from said inner face 112, 55 said slot 16 being adapted to receive a rubber band 20, one lap of which is exposed upon the outer face of the tongue 18.

In this manner the band 20 is exposed on the outer face of the device for engagement 60 with the sheet or card to be turned and the finger of the user is protected from said rubber band by means of the overhanging projecting portion of said inner face 112. By reason of the curvature of the shield 12, the 65 device is readily retained in operative position on the user's finger.

I claim:

1. A ring for handling paper sheets and the like, an enlarged shield carried thereby, 70 one end of said shield having an inwardly extending groove therein and providing a projecting tongue on the outer face of said shield, and a clinging member mounted upon said tongue having one portion disposed in 75 said groove and another portion exposed on the outer face of said tongue.

2. A ring for handling paper sheets and the like, an enlarged shield carried thereby, one end of said shield having an inwardly 80 extending groove therein and providing a projecting tongue on the outer face of said shield, and a clinging member mounted upon said tongue having one portion disposed in said groove and another portion exposed on 85 the outer face of said tongue, said shield being concaved slightly to receive the ball of the user's finger.

In testimony whereof I affix my signature.
MARY ALICE GIVENS.
